UNITED STATES PATENT OFFICE.

HARRY O. RUGH, OF SANDWICH, ILLINOIS, ASSIGNOR, BY MESNE ASSIGNMENTS, TO HALL SWITCH & SIGNAL COMPANY, A CORPORATION OF MAINE.

SUBSTATION SIGNAL-RECEIVING DEVICE.

1,106,680.

Specification of Letters Patent. Patented Aug. 11, 1914.

Continuation of application Serial No. 603,680, filed January 20, 1911. This application filed September 14, 1911. Serial No. 649,357.

To all whom it may concern:

Be it known that I, HARRY O. RUGH, a citizen of the United States, residing at Sandwich, in the county of Dekalb and 5 State of Illinois, have invented a certain new and useful Improvement in Substation Signal-Receiving Devices, of which the following is a full, clear, concise, and exact description, reference being had to the accompanying drawings, forming a part of this specification.

My invention relates to substation receiving devices used in signaling systems and has for its object the provision of a step-by-step 15 selective signaling device in which certain features of objectionable operation in prior devices are obviated. In the general form of such devices it has been customary to provide an arm preferably angularly displaced 20 from other arms of the other stations on the line and which arm is designed to make contact with a contact making device and if this contact is continued for a long enough period the said local signaling device operates. The arrangement generally has been such that if the arm makes but a momentary or passing contact with the contact making device that the signaling device does not respond. To prevent this response of the local 25 signaling device during the momentary contact when the arm is passing the contact making device when a station having a greater number of impulses is being called, it is necessary to make the adjustment of the local signaling device, which is usually a vibrating bell, very strong. By this, I mean that the spring or other retaining device which is associated with the armature must have a great amount of tension so that the 30 bell will not respond except when the current is continued for a long time. This, it will be seen, makes the operation of the bell marginal in that a weak current may not operate the said bell as against the strong 35 spring adjustment even though the current were long continued. It is of great advantage therefore that this marginal adjustment of the bell or local substation signal controlling device be eliminated. To eliminate this 40 objectionable feature is the object of my invention. The means which I use to accomplish this object, of course, are susceptible of

application to most, if not all, step-by-step systems, but I illustrate my invention herein as applied to a given particular system, which system also has some novel features. The application of my system for eliminating the marginal feature of the substation signal will be readily apparent to those skilled in the art.

In the explanation of the invention therefore in connection with the accompanying drawing, I wish it understood that this illustration is taken merely as an indication of one of the many forms in which the invention may be utilized.

I will describe one form of my invention more particularly by reference to the accompanying drawing in which:

Figure 1 diagrammatically sets forth a system constructed in accordance with my invention, and: Fig. 2 is a simplified diagrammatic view more clearly to reveal the circuit arrangements thereof.

In Fig. 1, I illustrate a central station A and substations B and C all united by line conductors 1 and 2. At the central station I show a battery 3, a push button 4, and a contact therefor 5. The elements 4 and 5 are merely illustrative of any suitable calling mechanism for sending impulses, if as in the specific illustration herein the substation devices are selected depending upon the number of impulses transmitted. At the substations I illustrate a step-by-step element 6 carrying an arm 7 adapted when in proper position to contact with a spring 8. A stop 9 is provided for the step-by-step element, and a spring 10 to restore it to normal against the stop 9, when certain operating pawls to be described later are released from engagement with said element 6. The arms 7 at the various substations occupy different angular positions so that different stations respond operatively by their signals to different numbers of impulses. A step-up pawl 11 actuated by an armature 12 steps up the element 6 in response to impulses. The armature 12 is under the control of a relay 13. A second pawl which I might call the holding pawl 14 is under the control of an armature 15, which armature is inductively associated with the relay 16. A back stop 17 is provided for the armature 12 and a front

stop 18 is provided for the armature 15. A back contact 19 is provided for the armature 15 and a front contact 20 is provided for the armature 12. A button 21 is preferably placed between the pawls 14 and 11 so that the pawl 11 is removed from element 6 by the pawl 14, and at the same time there will not be too much friction between these two pawls. A local signal 22 is provided which is so designed herein that it will operate by virtue of current furnished from the central station.

In associating the devices in circuit I have a conductor 23 which unites one terminal of the magnet 13 with the conductor 2. A conductor 24 unites the other terminal of the magnet 13 with the magnet 16 and a conductor 25 unites the other terminal of the magnet 16 with the line wire 1. The front contact 20 of the magnet 13 is by means of a conductor 26 connected to the conductor 24. A conductor 27 connects the conductor 25 with the spring 8. A conductor 28 connects one terminal of the bell 22 with the line wire 2. A conductor 29 connects the other terminal of the bell 22 with the back contact 19. A conductor 30 connects the arm 7 with the armature 15 and a conductor 31 connects the armature 15 with the armature 12. These circuit arrangements will be clear from an inspection of Fig. 2. It will then be seen that magnets 13 and 16 are arranged in series in a bridge across the line conductors 1 and 2. It will also be seen that the local bell 22 is arranged for bridge connection across the conductors 1 and 2 through circuit including conductor 28, bell 22, conductor 29, contact 19, armature 15, conductor 30, arm 7, spring 8, conductor 27, conductor 25 to line 1. It will also be seen that when the armature 12 is pulled up to engage the contact 20, the magnet 16 is short circuited by reason of the circuit that extends from line wire 2, conductor 23, magnet 13, conductor 24, conductor 26, contact 20, armature 12, conductor 31, conductor 30, arm 7, spring 8, conductor 27, to line wire 1. This means that there is practically a short circuit from the conductor 24 to the line wire 1, which short circuit extends around the magnet 16 and thus permits deenergization of same.

The operation of the system is as follows: The magnet 16 has two copper shells 32 so that this magnet is slow to release its armature 15. The first impulse transmitted from the central station A energizes both relays 13 and 16 so they attract their armatures 12 and 15. The attraction of the armature 15 permits pawls 11 and 14 to be thrown into engagement with the teeth of the step-by-step element 6. The required number of succeeding impulses is then sent to establish contact between the arm 7 and spring 8 of the particular substation which it is desired

to call. The time interval between impulses is so short that while armature 12 is released the armature 15 of the slow release magnet 16 does not fall back but permits the pawls 11 and 14 to remain in engagement with the teeth of the element 6. After the required number of impulses have been sent so that arm 7 engages spring 8, then the key 4 is held in its closed position, at which time elements 7 and 8 are in contact. This line circuit remaining closed, permits the circuit through elements 7 and 8 to remain closed, thereby short circuiting the magnet 16 and permitting its armature 15 to fall away and engage its back contact 19. This finally completes the circuit through the local signal 22, which thereupon operates by virtue of the current supplied from the battery 3. When the armature 15 is thus released, while the armature 12 remains attracted, only during the signaling operation, the pawl 14 bends and is not sufficiently strong to withdraw pawls 11 and 14 from the teeth of the element 6 on account of the pressure exerted by the pawl 11 against the tooth of the element 6, which it engages. After the signal 22 has been operated a sufficient length of time, key 4 is released and thereupon armature 12 is retracted, whereupon the spring action of the pawl 14 which tends to move it in an upwardly direction, disconnects pawls 11 and 14 from the teeth of the wheel 6 and permits the spring 10 to restore the element 6 to normal against its stop 9.

It will be understood that no closure of the local bell circuit can be made merely by the passing contact established between elements 7 and 8, as the element 7 passes the element 8 in its further movement in response to impulses of a greater number than are required for the particular station under consideration. The bell 22 thus need not be adjusted closely so as to avoid its operating on passing contacts. It requires the elapse of a certain time interval after the elements 7 and 8 have contacted at the particular station desired, during which the armature 15 is released to complete the bell circuit. No adjustment of the bell 22 therefore is necessary to avoid its operating on passing contacts. The great advantages of thus arranging the circuit and the elements to avoid this objectionable feature will be apparent.

The invention may of course be readily applied to many other systems with like benefits. As before stated, I am describing herein specifically one form which my invention may take without in any way intending to limit myself thereby, but

Having thus described one embodiment of my invention, what I claim as new and desire to secure by Letters Patent is:

1. A substation signal receiving device

having a step-by-step element, electro magnetic means for stepping said element to a pre-determined position, slow acting electro magnetic means for holding said element in its actuated position when energized, a signal controlling device under the control of said step-by-step element and means operable upon deenergization of said slow-acting means to close the circuit through said signal controlling device.

2. A substation signal receiving device having a step-by-step element, electro magnetic means for stepping said element to a pre-determined position, slow acting electro magnetic means for holding said element in its actuated position when energized, a signal controlling device under the control of said step-by-step element and means whereby said slow acting means controls the circuit through said signal controlling device.

3. A substation signal receiving device having a step-by-step element, electromagnetic means for stepping said element to a pre-determined position, slow acting electro-magnetic means for holding said element in its actuated position when energized, both of said electromagnetic means being operatively disconnected from said step-by-step element when said slow acting means is deenergized, a signal controlling device under the control of said step-by-step element and means operable upon deenergization of said slow acting means to close the circuit through said signal controlling device.

4. A substation signal receiving device having a step-by-step element, electromagnetic means for stepping said element to a pre-determined position, slow acting electro-magnetic means for holding said element in its actuated position when energized, both of said electromagnetic means being operatively disconnected from said step-by-step element when said slow acting means is deenergized, a signal controlling device under the control of said step-by-step element and means whereby said slow acting means controls the circuit through said signal controlling device.

5. A substation signal-receiving device having a signal circuit, a step-by-step signal circuit controlling element, electro-magnetic means to control the step-up operation of said step-by-step element to close the signal circuit at one point, electro-magnetic release-controlling means for said element including means to hold said step-by-step element and to control the final closure of said signal circuit controlled by said release-controlling means.

6. A substation signal-receiving device having a signal circuit, step-by-step means to control said signal circuit, electro-magnetic means to step-up said step-by-step means, electro-magnetic means to control the

release of said step-by-step means, and means whereby said step-by-step means effects control over said release-controlling electro-magnetic means only when said step-by-step means is in signal circuit closing 70 position.

7. A signal-receiving device having a step-by-step element, electro-magnetic step-up means for said element responsive to impulses, a signal circuit controlled by said element, means to render said signal circuit operative and to hold said step-by-step element and a release-controlling magnet for said step-by-step element under the control of said step-by-step element and also controlling said last means.

8. A signal-receiving device having a step-by-step element, electro-magnetic step-up means for said element responsive to impulses, slow-acting releasing electro-magnetic means therefor, a signal circuit controlled by said element, and means controlled by said slow-acting release-controlling electro-magnetic means to complete said signal circuit only upon deenergization of 85 said release-controlling electro-magnetic means.

9. A signal-receiving device having a step-by-step element, electro-magnetic step-up means for said element responsive to impulses, a signal circuit controlled by said element, auxiliary means to render said signal circuit operative, said auxiliary means maintaining said signal circuit inoperative during continuation of said impulses, and a 95 release-controlling magnet to hold said step-by-step element and control said auxiliary means to close said circuit upon deenergization of said releasing magnet.

10. A substation signal-receiving device 105 having a step-by-step signal circuit-closing element, a signal circuit controlled by said step-by-step element when said element is in its operative position, electro-magnetic means for controlling said element, and slow-acting means operable after the element setting operation to control the final closure of said signal circuit through said step-by-step element.

11. In a substation signal-receiving apparatus, the combination of a step-by-step element, a magnet therefor, holding means for said element, a magnet therefor, a local signal circuit therefor open at two points, one of said points being controlled by said stepping magnet, and the closure of the other point being dependent upon an extended closure of the other point.

12. In a substation signal-receiving device, the combination of a step-by-step signal circuit closing element, a step-up magnet therefor, holding means for said element, a holding magnet therefor, said magnets being in bridge of the line, a signal circuit open at two points, one of said points being 125 130

closed selectively by said element, and the other by said holding means upon the deenergization of said holding magnet.

13. In a substation signal-receiving device, the combination of a step-by-step element, a stepping magnet therefor, a holding device, a holding magnet therefor, said magnets being in bridge of the line, a signal circuit controlled by both of said magnets, and means whereby when said element is in circuit closing position, said stepping magnet

short-circuits said holding magnet whereby said signal circuit is completed by said holding means.

In witness whereof, I hereunto subscribe 15 my name this 31st day of August, A. D. 1911.

HARRY O. RUGH.
